UNITED STATES PATENT OFFICE.

JOHN W. GOODERHAM, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed October 16, 1920. Serial No. 417,422.

To all whom it may concern:

Be it known that I, JOHN WESLEY GOODERHAM, a citizen of the United States of America, residing at New York, in the 5 county of New York and State of New York, have invented certain new and useful Improvements in Telephone-Exchange Systems, of which the following is a full, clear, concise, and exact description.

10 This invention relates to a telephone exchange system in which connections are established through the medium of mechanical switching devices, and more particularly to means whereby a subscriber in an exchange 15 of this character may become connected to a distant exchange through a toll switching center.

In offices in which connections in the local area are established by mechanical switching devices without the services of a central office operator, it is customary to provide special operator's positions in the full mechanical office with which subscribers may become connected by dialing a single digit 0 20 for the purpose of giving the subscribers special service and for extending toll connections. In my co-pending application, Serial No. 417,421, filed on even date, I have disclosed one method which may be employed in extending toll connections from a 25 full mechanical office to a distant exchange, employing a toll recording trunk extending to a toll switching center of the originating exchange, from which center the connection 30 may be further extended in the usual manner over a toll trunk to a toll position of the distant exchange.

This method of extending toll connections is quite satisfactory for short haul traffic, that is, where the exchanges are not 35 widely separated and no great lapse of time intervenes between the extension of the toll connection by the special operator to the toll switching center, and the successful extension of the connection from the switching center to the line of the desired subscriber in the distant exchange. If, however, the exchanges are widely separated and the traffic between them is heavy, there 45 may be considerable delay before the toll operator at the switching center can obtain

an assignment of a toll trunk and a connection through a distant exchange to the desired line. Where there is such considerable delay, it is not desirable to maintain the 55 special operator in on the connection and thereby prevent the use of her cord and district selector for extending other connections which may, in the meantime, come in to her position.

60 To obviate this difficulty, it is a feature of this invention to provide a holding cord at the special operator's position by means of which she may hold the connection extending to the calling subscriber's line while she 65 proceeds to transfer the call to the toll switching center and while the toll operator at the toll switching center is obtaining the desired connection, thereby permitting her 70 to take down the cord circuit by means of which she initially answered the call. The holding cord is single ended and terminates in the bank of a final selector switch of the full mechanical office and is accessible from the toll switching center through a cordless 75 operator's position and final selector switch. Thus, the toll operator at the toll switching center may obtain a connection over the toll line to the line of the desired subscriber in the distant exchange, and connect such line 80 through the holding cord to the line of the calling subscriber. In this manner the special operator's time is not consumed waiting on the delayed establishment of toll connections or in supervising such established toll 85 connections, it being far more economical to transfer supervision of such connections to the recording operator at the toll switching center and to hold connection with the calling line over a cordless trunk, the cordless 90 operator being required only to establish and release the connection through her position.

95 It is therefore an object of the invention to provide an efficient means for establishing toll connections outgoing from a full mechanical office, which obviates the unnecessary tying up of the special operator's equipment while awaiting the extension of the toll connection to the desired line.

100 It is a further object of the invention to provide a holding cord circuit at the spe-

cial operator's position, the terminals of which are accessible from a toll switching center through which a revertive connection may be established with the calling line 5 after connection has been successfully established with the desired called line.

- These and other objects of the invention will be more readily understood by reference to the accompanying drawings in which 19 Fig. 1 shows a schematic representation of the circuits employed in the establishment of a toll connection from the line of a subscriber A in the office X, through a toll switching center Y to a subscriber's line B in an office Z of a distant exchange; Fig. 2 shows a holding cord associated with the special operator's position of the office X which terminates in the terminal banks of final selector switches of the same office; 25 Fig. 3 shows the circuits of a final selector switch together with the controlling circuits associated therewith, in the terminal bank of which the holding cord of Fig. 2 terminates; and Fig. 4 shows an incoming selector switch at the cordless operator's position accessible from the toll switching center and having access to the circuits of final selector switches, together with the controlling circuits associated therewith, and a 30 sending mechanism under the control of the cordless operator for controlling said switches, said sending mechanism being represented by the apparatus shown in the dotted rectangle.
- 35 It will be assumed for convenience in disclosing the invention that the subscriber's line A terminates in a full mechanical office X of the general type disclosed in the patent to F. A. Stearn and F. J. Scudder, 1,395,977, 40 issued November 1, 1921, and that the called subscriber's line terminates in the office Z of a distant exchange, and that a toll connection is established between the subscriber's line through the toll switching center Y 45 of the originating exchange.
- In general the system functions in the following manner: the subscriber A desiring a connection with the line of subscriber B in the distant exchange removes his receiver from the switch-hook and through the operation of the line switch 100 becomes connected to a trunk line terminating in a district selector 101. The subscriber then proceeds to dial the two digits required and 50 through the operation of the sender 102, associated with the full mechanical office, in response to the digits dialed, obtains a connection with the trunk circuit 103 extending to a special operator's position 0. The 55 special operator, upon answering the call, ascertains the number and exchange designations of the desired line and proceeds to set up the proper routing upon the keyboard of her sending mechanism 104 for setting 60 the district selector switch 105, in which her 65

cord circuit 106 terminates, upon the terminals of an idle toll trunk 107 extending to the toll switching center Y.

In response to the extension of the connection to the toll switching center Y, an idle operator at such position answers the call with a cord circuit 108. The special operator at position 0 has, in the mean time, selected an idle holding cord 200 and connected it with the multiples of the trunk circuit 103 for holding the calling line, and now upon the response of the toll operator transmits to the toll operator the number and exchange designation of the desired line and the terminal number assigned to the holding cord taken for use and then takes down her cord 106 freeing the selector switch 105 and the sender 104 for use in extending other connections. 75

The toll operator at the switching center Y disconnects the answering plug of a cord 108 from the trunk line 107 and connects it with the trunk line 416 extending to the cordless operator's position 0' of office X and transmits to the cordless operator the number of the holding cord 200 which the special operator has employed, and proceeds to obtain the assignment of a toll line extending to the distant exchange. Through the co-operation of the toll and terminating operators at such exchange she then obtains a connection with the desired line B. 85

The cordless operator in response to the instructions of the toll operator then sets up the number of the holding cord upon her sender 417 which then causes the setting of the incoming selector switch 418, in which the trunk line 416 terminates, and the setting of the final selector switch 350 upon the terminals of the holding cord 200. Upon the extension of a connection between the holding cord and the toll operator's position, the toll operator instructs the calling subscriber to hang up his receiver while awaiting the extension of the connection to the desired line. The calling subscriber A is then signalled, upon the successful extension of the connection and conversation may then take place between the subscriber A and subscriber B as soon as subscriber A 10 11 responds to the signal. 11

The apparatus employed in extending a connection to the toll switching center is identical with that shown and described in my aforesaid co-pending application and since it forms no essential part of the present invention has been disclosed only in a schematic manner in Fig. 1. 12

The holding cord circuit 200 shown in Fig. 2 is of the single plug ended type terminating in multiple terminals appearing in the banks of final selector switches, and is arranged to transfer the supervision of the calling line from the special operator's position to the toll operator's position in the toll switching 12 13

center Y, as soon as the holding cord is connected to the toll switching center.

The selector switches 350 and 418 shown in Figs. 3 and 4, are of the general type disclosed in the patent to Craft and Reynolds No. 1,123,696, issued January 5, 1915. For controlling the circuits associated with these switches, auxiliary switches 300 and 400 of the sequence switch type, disclosed in the patent to Reynolds and Baldwin No. 1,127,808, issued February 9, 1915, are employed. These switches comprise switch shafts carrying a plurality of contact operating cams 301 to 316 inclusive and 401 to 415 inclusive respectively, which in different angular positions of the switch shaft effect the closure of the respective circuits of the selector switches. Cams 301 and 401 are master cams and open the contacts associated therewith only in the positions indicated by the numerals applied adjacent thereto. The remaining cams close their respective contacts only in the positions indicated by the numerals applied adjacent thereto.

The selector switches 350 and 418 are selectively controlled by an office sending mechanism, 417 diagrammatically represented by the apparatus enclosed in the dotted rectangle marked sender, shown at the bottom of Fig. 4. This sender is of the well-known type such as is disclosed in the patent to Lundell No. 1,168,319 issued January 18, 1916 but since it enters only incidentally into the disclosure of this invention and forms no essential part thereof, a schematic disclosure thereof is thought to be sufficient.

The apparatus employed and the general method of operation of the system having now been briefly described, a detailed description of the method of establishing a connection will now be given in order to better disclose the salient features of the invention. The subscriber A desiring a toll connection with the subscriber B removes his receiver from the switch-hook and in the manner previously described, through the operation of the line switch 100 and the district selector switch 101 obtains a connection with the trunk circuit 103 extending to a special operator's position 0. The special operator in response to the call inserts the plug of a cord circuit 106 in the jack of the trunk 103 and ascertains from the calling subscriber the exchange and number designation of the desired line. It has been assumed that the subscriber desired is in an exchange quite distant from the originating exchange and to which the traffic is heavy. The special operator at position 0 does not attempt to establish a direct connection over the recording trunk 107 and through the toll switching center Y, since considerable time may elapse before a successful call is established with the sub-

scriber's line B and it is undesirable to tie up equipment at her position and the recording trunk 107 during the establishment of the connection. The operator at position 0 therefore inserts the plug P of a holding cord circuit into a multiple of the trunk circuit 103 for the purpose of holding the connection between the calling subscriber's line and her position so that she may take down the connection which she originally established in answering the call.

Upon the insertion of the plug P in the multiple jack J of the trunk circuit 103, a circuit is closed from grounded battery, through the winding of sleeve relay 201, sleeve contact 202 of the plug P, sleeve contact 203 of the jack J, and thence to ground through the winding of sleeve relay 204 of the trunk circuit 103. Both relays 201 and 204 energize in this circuit, relay 204 establishing a holding circuit through the winding of slow to release relay 205 which may be traced from grounded battery, through the winding of relay 205 and thence to ground through the armature and front contact of relay 204. Relay 205 upon energizing connects ground potential to the sleeve conductor 206 of the trunk circuit 103 for the purpose of maintaining the district selector 101 and the subscriber's line switch 100 in their operated positions so that the calling subscriber may restore his receiver to its switch-hook while awaiting the establishment of the desired toll connection without causing the release of the connection which has been established from his line to the special operator's position.

Sleeve relay 201 upon energizing closes a circuit for the supervisory lamp 207, which circuit may be traced from grounded battery through the lamp 207, left-hand armature and front contact of relay 201, the armature and back contact of relay 208, and thence to ground at the right hand armature and back contact of relay 209. Lamp 207 does not however become illuminated since this operating circuit is immediately opened at the armature and back contact of relay 208, which relay becomes energized as soon as connection is made with the trunk 103. The circuit of relay 208 may be traced from grounded battery, through the right-hand winding of relay 208, inner left-hand armature and back contact of relay 210, ring conductor 218 of the holding cord circuit 200, ring contacts of plug P and jack J and thence over the ring conductor of the trunk circuit 103 through the lower brushes of selector switch 101 and switch 100, over the subscriber's line loop, through the upper brushes of line switch 100 and selector switch 101, tip conductor of trunk 103, tip contacts of jack J and plug P, tip conductor 219 of the cord circuit, the outer left-hand armature and back contact of relay 210 and

- thence to ground through the left-hand winding of relay 208. Relay 201 at its right hand armature and front contact closes a circuit for supervisory lamp 211, 5 extending from grounded battery through the lamp 211, left-hand armature and back contact of relay 209 and thence to ground at the right hand armature and front contact of relay 201.
- 10 The operator at position 0 upon noting the illumination of lamp 211 throws her listening key 212 to connect her telephone set with the strands of the holding cord circuit 200. Upon the depression of the listening key 212, the contacts 213 associated with the key are closed for establishing a circuit for relay 214. This circuit may be traced from grounded battery through the left-hand winding of relay 214 and thence 15 to ground through the contacts 213. Relay 214 upon energizing establishes a locking circuit for itself extending from grounded battery through lamp 207, the left-hand armature and front contact of relay 201, the armature and front contact of relay 208 and thence to ground through the right-hand armature and front contact and right-hand winding of relay 214.
- 19 The operator at position 0 now withdraws 20 the answering plug of the cord circuit 106 which she has employed to answer the call, and then proceeds through the setting of her sender 104 to set the district selector 105 of the cord circuit 106 upon the terminals of a recording toll trunk 107 extending to the toll switching center Y. The operator at the toll switching center answers the call on the trunk 107 by means of a cord circuit 108 and receives from the operator at position 0 the exchange and number of the subscriber desired, the number of the holding trunk 200 which the special operator has employed and such other information in connection with the call as is necessary to be recorded upon her ticket. After 25 having transmitted this information, the operator at position 0 may then release the apparatus at her position in readiness for establishing other calls.
- 20 The operator at the toll switching center Y now communicates over an order wire circuit (not shown) with the operator at the cordless position 0', shown in Fig. 4, and obtains from the cordless operator the assignment of a cordless trunk circuit, such as 416, extending from the cordless operator's position to the toll switching center, and transmits to the cordless operator the number of the holding cord 200 which she 30 has recorded upon her ticket.
- 25 The operator at the toll switching center Y now withdraws the answering plug of her cord circuit 108 from the answering jack of the trunk circuit and connects it with the jack of the assigned cordless trunk 416. A circuit is now established over the tip conductor of the trunk circuit, through the upper right hand winding of repeating coil 419, left-hand armature and back contact of relay 420 and thence to ground through the right hand winding of line relay 421, and a circuit is established over the ring conductor of the trunk circuit through the lower right hand winding of repeating coil 419, normally closed make contacts of the right hand armature of relay 420 and thence to grounded battery through the left-hand winding of relay 421. Relay 421 energizes in this circuit closing at its armature and front contact a circuit for relay 422. This circuit may be traced through the left-hand winding of relay 422, lower left-hand contact of sequence switch cam 402, upper right hand contact of sequence switch cam 403 and thence to ground at the armature and front contact of relay 421. Relay 422 upon energizing closes a circuit for lamp 423, which circuit extends from grounded battery through lamp 423, the upper contacts of sequence switch cam 404, left-hand armature and front contact of relay 422 and thence to ground through the left-hand contacts of sequence switch cam 405.
- 20 The operator in response to the signal from lamp 423 operates starting key 424, if she has not already operated it immediately upon the assignment of the trunk and before the toll operator has connected with the cordless trunk 416. The operation of key 424 establishes a circuit for driving the sequence switch 400 out of position 1 and into position 2, this circuit extending from grounded battery, through the driving magnet of sequence switch 400, lower right-hand contact of sequence switch cam 406 and thence to ground through the contact of key 424. As soon as sequence switch 400 leaves position 1 the circuit of relay 422 is opened and the lamp 423 is then maintained lighted over a circuit extending from grounded battery, through the lamp and thence to ground through contacts of sequence switch cam 407 until a sender has been selected and associated with the trunk circuit 416.
- 25 With sequence switch 400 in position 2, a circuit is established over the starting conductor 425 for starting up a trunk finder for associating the sender 417 with the cordless trunk 416. Since this selector switch is of the ordinary type and has no direct bearing upon this invention, it has not been disclosed. The starting circuit may be traced from conductor 425 through the lower left-hand contact of sequence switch cam 408, right-hand armature and back contact of relay 422 and thence to ground at the lower left-hand contact of sequence switch cam 407. As soon as the sender selector finds trunk 416, which trunk 30

is marked as in a calling condition by ground connected to the upper right-hand contact of sequence switch cam 409, a circuit is established over the conductor 426 for arresting the selecting movement of the selector switch. This circuit may be traced from ground, through the right-hand contacts of sequence switch cam 409, left-hand armature and back contact of relay 422, and thence to the conductor 426 through the left-hand contacts of sequence switch cam 410.

As soon as the sender is associated with the cordless trunk 416, a sequence switch (not shown) but associated with the sender, advances to position 5 and at its cam 427 closes a circuit for advancing sequence switch 400 out of position 2 and into position 3. This circuit may be traced from grounded battery, through the winding of magnet 400, lower left-hand contact of sequence switch cam 411 (2) and thence to ground through the sequence switch cam 427.

As soon as sequence switch 400 leaves position 2, the circuit over starting conductor 428 is opened and a circuit is established over conductor 428 for holding the sender in association with the cordless trunk 416. This circuit extends from conductor 428 to ground through the right-hand contacts of sequence switch cam 410. Sequence switch 400 upon reaching position 3 closes a circuit for supervisory lamp 429, extending from grounded battery through lamp 429, lower contacts of sequence switch cam 404 and thence to ground at interrupter 430 and the lamp 429 thereupon flashes and continues to flash until selection has been completed. Lamp 423 is now extinguished since sequence switch 400 opened the circuit of this lamp at cam 407 as soon as a sender was associated with the cordless trunk 416.

With sequence switch 400 in position 3 a fundamental circuit is established extending through the winding of relay 422 and the windings of stepping relay 431 of the sender, which circuit may be traced from grounded battery through the left-hand winding of relay 422, lower left-hand contact of sequence switch cam 402, lower right-hand contact of sequence switch cam 403, the windings of stepping relay 431 and thence to ground through the armature and back contact of relay 432. Relay 422 upon energizing closes a circuit for driving sequence switch 400 out of position 3 and into position 5, this circuit extending from grounded battery, through the magnet winding of sequence switch 400, upper left-hand contact of sequence switch cam 406, right-hand armature and front contact of relay 422 and thence to ground at the left-hand contact of sequence switch cam 407.

As soon as sequence switch 400 leaves position 4, the energizing circuit previously traced for relay 422 is opened at the lower left-hand contact of sequence switch cam 402, but relay 422 remains locked up to the fundamental circuit over a circuit extending from grounded battery through its left-hand winding, upper left-hand and lower right-hand contacts of sequence switch cam 409, left-hand armature and front contact of relay 422, upper left-hand contact of sequence switch cam 403 and thence over the fundamental circuit as previously traced.

As soon as sequence switch 400 reaches position 5, a circuit is established for the up drive magnet 433, which circuit may be traced from grounded battery, through the winding of magnet 433, lower left-hand and upper right-hand contacts of sequence switch cam 412, right-hand armature and front contact of relay 422 and thence to ground at the left-hand contact of sequence switch cam 407. Magnet 433 upon energizing presses the depending portion of the shaft 434 of selector switch 418 against the constantly rotating up drive roller 435, thereby causing the switch shaft to move upwardly in its brush selection movement.

During its upward movement an intermittent shunt to ground is connected to the fundamental circuit between the windings of relay 422 and of stepping relay 431 for the purpose of counting down the counting relays of the sender in accordance with the first digit of the number set up on the sender, in the well known manner. This intermittent shunt is applied to the fundamental circuit over a circuit which may be traced from ground at sequence switch cam 413, conductor 436, brush 437, brush selection segment 438 of the commutator 439, conductor 440, the upper left-hand contact of sequence switch cam 402 and thence to a junction point in the fundamental circuit between the windings of relays 422 and 431 at sequence switch cam 403. The switch shaft 434 continues in its upward movement until the zero counting relay of the sender becomes energized when the relay 432 is energized to open the fundamental circuit.

Upon the opening of the fundamental circuit relay 422 deenergizes, closing at its right-hand armature and back contact a circuit for driving sequence switch 400 out of position 5 into position 6. This circuit may be traced from grounded battery through the winding of the driving magnet of sequence switch 400, the lower left-hand contacts of sequence switch cam 406, right-hand armature and back contact of relay 422 and thence to ground at the left-hand contact of sequence switch cam 407. Relay 422 also upon deenergizing opens the circuit of up drive magnet 433 to arrest the upward

movement of the switch shaft. A set of brushes, which it will be assumed is the set disclosed in the drawing, is now positioned with relation to the tripping spindle to be tripped upon the energization of tripping magnet 422 and a subsequent upward movement of the switch shaft. As soon as sequence switch 400 reaches position 6, the circuit of tripping magnet 442 is completed, 10 extending from grounded battery through the winding of magnet 442 and thence to ground through the lower left-hand contact of sequence switch cam 413.

With sequence switch 400 in position 6 15 the fundamental circuit previously traced through the left hand winding of relay 422 and the windings of stepping relay 431 is again established. Relay 422 upon energizing over the fundamental circuit closes a 20 circuit for driving sequence switch 400 out of position 6 and into position 7, which circuit extends from grounded battery, through the winding of the driving magnet of the sequence switch, the upper left hand contact of sequence switch cam 406, right hand armature and front contact of relay 422 and thence to 25 ground at the left hand contact of sequence switch 407. When sequence switch 400 leaves position 8, if the lowermost set of bank terminals in the selected group upon which the tripped set of brushes are arrested are the 30 terminals of an idle trunk, then relay 422 immediately deenergizes thereby preventing the establishment of a circuit from the up drive magnet 433 when the sequence switch reaches position 9.

35 The circuit of the up drive magnet 433 is now re-established and the switch shaft 434 is driven upwardly in its group selection movement to position the selected set of brushes in association with the desired group of bank terminals. During the initial portion of the upward movement of the switch shaft the selected set of brushes is tripped and thereafter an intermittent ground is connected to the fundamental circuit for shunting down the stepping relay 431 of the sender to operate the counting relays of the sender in the well known manner. This shunt circuit may be traced from ground at the upper left hand contact of 40 sequence switch cam 413, conductor 436, brush 443, group selection segment 444 of the commutator 439, conductor 445, right hand contact of sequence switch cam 402 and thence to the fundamental circuit at sequence switch cam 403.

45 As soon as the switch shaft 434 has moved upwardly to such an extent as to satisfy the setting of the counting relays of the sender, relay 432 at the sender becomes energized to open the fundamental circuit, thereby 50 causing the deenergization of relay 422. Relay 422 upon deenergizing opens the circuit of the updrive magnet 433 to arrest the selected set of brushes in contact with the 55 lowermost set of terminals in the selected

group of bank terminals and closes at its right hand armature and back contact the previously traced circuit for driving sequence switch 400 out of position 7 and into position 8.

With sequence switch 400 in position 8, a circuit is established for relay 422 which may be traced from grounded battery, through the right hand winding of this relay and thence to ground through the lower 75 right hand and upper left hand contacts of sequence switch cam 405. Relay 422 upon energizing closes a circuit for advancing sequence switch 400 out of position 8 and into position 9, this circuit extending from 80 grounded battery, through the winding of the driving magnet of the sequence switch, the upper left hand contact of sequence switch cam 406, right hand armature and front contact of relay 422 and thence to 85 ground at the left hand contact of sequence switch 407. When sequence switch 400 leaves position 9, if the lowermost set of bank terminals in the selected group upon which the tripped set of brushes are arrested are the 90 terminals of an idle trunk, then relay 422 immediately deenergizes thereby preventing the establishment of a circuit from the up drive magnet 433 when the sequence switch reaches position 9.

If, however, the first set of terminals in the selected group are the terminals of a busy trunk, then relay 422 locks up with the sequence switch in position 8 over a circuit extending from grounded battery, through the left hand winding of relay 422, the lower left hand contact of sequence switch cam 402, upper left hand contact of sequence switch cam 403, the left hand armature and front contact of relay 422, lower contacts of sequence switch cam 409, test brush 446 and thence to ground at the test terminal 447 of the first busy trunk of the selected group. This locking circuit is maintained after sequence switch 400 reaches position 9 and therefore with sequence switch 400 in position 9 and relay 422 energized, a circuit is established for updrive magnet 433 which may be traced from grounded battery, through the winding of magnet 433, lower 105 left hand and upper right hand contacts of sequence switch cam 412, right hand armature and front contact of relay 422 and to ground at the left hand contact of sequence switch 407. In response to the energization of the up drive magnet 433, switch shaft 434 is driven upwardly in its hunting movement or until the test brush 446 encounters the test terminal of an idle trunk leading to an idle 110 final selector switch.

115 It will be assumed that the first idle trunk encountered is the trunk shown which terminates in the bank terminals 448, 449 and 450, and that therefore relay 422 is maintained locked up until the test brush 120 125

446 encounters test terminal 448 of this trunk. As soon as connection is made with this idle trunk, the locking circuit of relay 422 is opened and relay 422 deenergizes following the centering of the brushes 446, 451 and 452 upon the terminals 448, 449 and 450, relay 422 being maintained energized until the brushes are properly centered over a centering locking circuit extending from 5 grounded battery, through its right hand winding, the right hand contacts of sequence switch cam 405, conductor 453, centering segment 454 of commutator 439, brush 455, upper contacts of sequence switch cam 412, 10 right hand armature and front contact of relay 422 and thence to ground at the left hand contact of sequence switch cam 407. Upon the deenergization of relay 422, the circuit of up drive magnet 433 is opened to 15 arrest the upward movement of the switch shaft and a circuit is established for driving sequence switch 400 out of position 9 and into position 11; this circuit extending from grounded battery, through the winding of 20 the driving magnet of the sequence switch, the lower left hand contact of sequence switch cam 406, right hand armature and back contact of relay 422 and thence to ground at the left hand contact of sequence 25 switch cam 407.

With sequence switch 400 in position 11, a circuit is established for placing a busy potential upon the test terminal 448 of the selected trunk circuit, extending from ground 30 at the upper right hand contact of sequence switch cam 409, the lower left hand contact of cam 409, and thence through test brush 446 to the test terminal 448. The fundamental circuit is now dis-associated from 35 the relay 422 of the selector switch 418 and is extended over the lower right hand and upper left hand contacts of sequence switch cam 414, brush 452, bank terminal 450, conductor 317, lower right hand contact of sequence switch cam 302, lower right hand contact of sequence switch cam 303, through the left hand winding of line relay 318 of the final selector switch 350 and thence to 40 grounded battery through the right hand contact of sequence switch cam 304. At the lower contact of sequence switch cam 415, the advance lead 456 is extended from the sender over the brush 451 and bank terminal 449 of the selector switch 418 to the trunk 45 conductor 319 and thence through the upper right hand and lower left hand contacts of sequence switch cam 305, through resistance element 320 to ground at the lower right hand contact of sequence switch cam 306 for a purpose to be later described.

Upon the extension of the fundamental circuit to the final selector switch 350, relay 318 of the final selector switch and stepping relay 431 of the sender energize. 50 Relay 318 closes a circuit for relay 321

which may be traced from grounded battery through the right hand winding of relay 321, conductor 322, upper right hand contact of sequence switch cam 307, conductor 323, right hand armature and front contact of relay 318 and thence to ground through the upper contact of sequence switch cam 308. Relay 321 energizes in this circuit and at its right hand armature and front contact closes a locking circuit for 55 itself extending from grounded battery through its right hand winding, the armature and back contact of test relay 324, right hand armature and front contact of relay 321, sleeve conductor 325, bank terminal 448, and brush 446 of the incoming selector switch 418 and thence to ground at sequence switch cam 409. Relay 321 upon energizing closes a circuit for driving sequence switch 300 out of normal position 1 into position 2, 60 which circuit may be traced from grounded battery through the winding of the driving magnet of sequence switch 300, the lower contacts of sequence switch cam 309 and thence to ground at the left hand armature 65 and front contact of relay 321. When sequence switch 300 moves out of position 1, the initial energizing circuit of relay 318 is opened at the lower right hand contact of sequence switch cam 303, but relay 318 remains energized over the fundamental circuit by reason of a locking circuit extending from grounded battery through the right hand contact of sequence switch cam 304, left hand winding of relay 318, lower left hand contact of sequence switch cam 310, left hand armature and front contact of relay 318, lower left hand contact of sequence switch cam 303 and thence through the lower right hand contact of sequence switch cam 302 and over the fundamental circuit as previously traced. 70

Relay 318 upon energizing, with sequence 75 switch 300 in position 2, closes a circuit for the high speed up drive magnet 326 which circuit may be traced from grounded battery through the winding of magnet 326, the upper left hand contact of sequence switch cam 311, conductor 323, right hand armature and front contact of relay 318 and thence to ground at the upper right hand contact of sequence switch cam 308. Magnet 326 upon energizing presses the depending portion of switch shaft 327 against the 80 constantly rotating high speed roller 328 thereby causing the switch shaft to be moved upwardly at a high speed in its brush selection movement. During the upward movement of the switch shaft an intermittent ground is connected to the circuit for intermittently shunting down stepping relay 431 of the office sender, over a circuit which may be traced from a junction point between the windings of relay 431 and relay 318 (sequence switch cam 302), 85

through the upper left hand contact of sequence switch cam 302 (1 $\frac{1}{4}$ to 2), conductor 329, brush selection segment 330 of the commutator 331, brush 332, conductor 333 and thence to ground through the upper right hand contact of sequence switch cam 306 (13 to 11).

After the initial closure of the fundamental circuit through the winding of relay 318 and the windings of sender stepping relay 431, in response to the intermittent shunting of the windings of the stepping relay 431, the stepping relay 431 in the well known manner causes the successive operation of the counting relays of the sender until the switch shaft 327 has moved upwardly to such an extent as to satisfy the sender when the relay 432 of the sender energizes, opening the fundamental circuit.

Relay 318 of the final selector switch thereupon deenergizes and at its right hand armature and front contact opens the energizing circuit of the up drive magnet 326 to arrest the upward movement of the switch shaft and at its right hand armature and back contact closes a circuit for driving sequence switch 300 out of position 2 and into position 3, this circuit extending from grounded battery through the winding of the driving magnet of sequence switch 300, upper left hand contact of sequence switch cam 312, right hand armature and back contact of relay 318 and thence to ground at the upper contact of sequence switch cam 308. A set of brushes, assumed to be the brushes shown, corresponding to the setting of the sender has now been positioned with relation to the tripping fingers on the tripping spindle 334, so that upon the later energization of the tripping magnet 335 and the subsequent upward movement of the switch shaft this set of brushes will be tripped for engagement with the bank of 100 terminals with which this brush is associated. To cause the tripping of this set of brushes, the tripping magnet 335 is energized over a circuit extending from grounded battery, through the winding of tripping magnet 335 and thence to ground at the lower left hand contact of sequence switch cam 306 as soon as sequence switch 300 reaches position 3.

When sequence switch 300 reaches position 3, the energizing circuit of relay 318 is again established over the fundamental circuit as previously described and relay 318 and stepping relay 431 of the office sender energize. Relay 318 upon energizing again closes the previously traced circuit for driving sequence switch 300 out of position 3 and into position 4. With sequence switch 300 in position 4, the previously traced circuit for the up drive magnet 326 is again established at the right hand armature and front contact of relay 318. Relay 318 also

establishes the previously traced locking circuit for itself extending through its left hand armature and front contact for maintaining itself energized over the fundamental circuit after sequence switch 300 leaves position 3 and opens the initial energizing circuit at the lower right hand contact of sequence switch cam 303. Upon the energization of the high speed up drive magnet 326, the switch shaft 327 is driven upwardly in its group of tens selection movement and during the initial portion of this movement the selected set of brushes is tripped by the tripping spindle 334. During the remainder of the group selecting movement the tripped set of brushes travel upwardly in contact with the terminals of the bank with which the brush set is associated. During the group selection movement of the switch shaft an intermittent ground is connected to the fundamental circuit through the junction point (sequence switch cam 302) over a circuit extending through the upper left hand contact of sequence switch cam 303 (3 $\frac{1}{4}$ to 4), conductor 336, group selection segment 337, of the commutator 331, brush 338, conductor 333 and thence to ground through the upper right hand contact of sequence switch cam 306.

In response to the intermittent connection of the shunt circuit to the fundamental circuit, stepping relay 431 of the sender operates the counting relays of the sender in succession until the switch shaft 327 has moved upwardly to such an extent as to satisfy the setting of the sender when relay 432 of the sender is energized to open the fundamental circuit. As soon as the fundamental circuit is opened, relay 318 deenergizes opening the circuit of the up drive magnet 326 to arrest the upward movement of the switch shaft with the tripped set of brushes in engagement with the lowermost set of terminals in the selected group. Relay 318 also closes the circuit previously traced for driving sequence switch 300 out of position 4 and into position 5. In position 5 the fundamental circuit extending through the winding of stepping relay 431 of the sender and the left hand winding of relay 318 is again established and relay 318 upon energizing closes the previously traced circuit for driving sequence switch 300 out of position 5 and into position 6 and the previously traced locking circuit for itself which is maintained after sequence switch 300 reaches position 6.

Upon reaching position 6 a circuit is established for the low speed up drive magnet 339 which circuit may be traced from grounded battery, through the winding of magnet 339, lower right hand contact of sequence switch cam 307, conductor 323, right hand armature and front contact of relay 318 and thence to ground at the upper con-

tact of sequence switch cam 308. The low speed up drive magnet 338 upon energizing presses the depending portion of the switch shaft 327 against the constantly rotating low speed roller 340 thereby causing the upward movement of the switch shaft in its units selection movement. During this upward movement of the switch shaft an intermittent ground is connected to the junction point (sequence switch cam 302) in the fundamental circuit between the winding of sender stepping relay 431 and the winding of relay 318, over a circuit which may be traced from the upper left hand contact 15 of sequence switch cam 302 (5 $\frac{3}{4}$ to 6) conductor 329, centering portion of commutator segment 330, brush 332, conductor 333 and thence to ground through the upper right hand contact of sequence switch cam 306. 20 In response to the intermittent connection of the above traced shunt circuit to the fundamental circuit, the stepping relay 431 of the office sender is intermittently operated to operate the counting relays of the sender 25 in succession until the switch shaft 327 has moved upwardly to such an extent as to satisfy the setting of the sender, when relay 432 of the sender energizes to open the fundamental circuit. When the fundamental circuit is opened, relay 318 deenergizes, opening the circuit of the up drive magnet 339 to arrest the upward movement of the switch shaft, and closes the previously 30 traced circuit for driving sequence switch cam 300 out of position 6 and into position 9. Relay 318, however, does not deenergize until the selected set of brushes are properly centered upon the selected set of bank terminals, since it is maintained energized over 35 the shunt circuit previously traced through the centering portion of the commutator segment 330.

The brushes of the final selector switch 350 have now been positioned upon the terminals of the holding cord circuit 200, the number of which was transmitted to the cordless operator by the toll operator at the toll switching center. When sequence switch 300 reaches position 9 a circuit is closed for re-energizing relay 318, which circuit may be traced from grounded battery through the right hand contact of sequence switch cam 304 (1 to 10) the left hand winding of relay 318, lower left hand and upper right hand contacts of sequence switch cam 310 and thence to ground at the left hand armature and front contact of relay 321. Relay 318 upon energizing closes a locking circuit for itself extending from grounded battery, through its left hand winding, lower left hand contact of sequence switch cam 310, left hand armature and front contact of relay 318 and thence to ground through the upper contacts of sequence switch cam 318. This locking circuit will be maintained through position 10 of sequence switch 300. Relay 318 upon energizing also closes the circuit as previously traced for driving sequence switch 300 out of position 9 and into position 12. Upon reaching position 10, a new holding circuit is established for relay 318 extending from grounded battery, right hand winding of relay 318, lower left hand contact of sequence switch cam 315, right hand armature and front contact of relay 318 and thence to ground at the upper right hand contact of sequence switch cam 308. 70 Upon reaching position 11 sequence switch 300 established a new holding circuit for relay 318 extending from ground, through the winding of test relay 324, conductor 341, upper right hand contact of sequence switch cam 302, lower right hand contact of sequence switch cam 303, left hand winding of relay 318, upper left hand contact of sequence switch cam 310, left hand armature and front contact of relay 318, left hand contacts of sequence switch cam 313, test brush 342, and thence over bank terminal 343 and winding of sleeve relay 209 of the holding cord circuit to ground. Since now the holding circuit of relay 318 extends from ground through its left hand winding and the winding of relay 209, to ground, relay 318 will become deenergized as soon as sequence switch 300 leaves position 11 and neither relays 324 nor 209 will energize at this time. When, therefore, relay 318 deenergizes it closes a circuit for driving sequence switch 300 out of position 12 and into position 13, this circuit extending from grounded battery, magnet 300, through the upper left hand contact of sequence switch cam 312, right hand armature and back contact of relay 318, lower right hand contact of sequence switch cam 308 (12) and thence to ground at the left hand armature and front contact of relay 321. Upon reaching position 13, a circuit is established over the lower contacts of sequence switch cam 309 and the left hand armature and front contact of relay 321 for driving sequence switch 300 out of position 13 and into position 14 and in position 14 a circuit is established as previously traced through the winding of the driving magnet of sequence switch 300, right hand armature and back contact of relay 318, and thence to ground at the upper contact of sequence switch cam 308 for driving sequence switch 300 into the talking position 15, in which position the trunk conductors 317 and 319 are connected respectively to the brushes 352 and 353 over the lower contacts of sequence switch cam 302 and the upper contacts of sequence switch cam 305. 100 105 110 115 120 125 130

As soon as sequence switch 300 reaches position 15 a circuit is established over the test brush 342 and the sleeve conductor of the cord circuit 200 for energizing the sleeve

relay 209 of the cord circuit. This circuit may be traced from grounded battery, through the left hand contact of sequence switch cam 304, the lower contacts of sequence switch cam 313, test brush 342, bank terminal 343, sleeve conductor 215 and thence to ground through the winding of sleeve relay 209. Relay 209 energizing in this circuit closes a circuit for relay 210 extending from grounded battery, winding of relay 210 and thence to ground through the right hand armature and front contact of relay 209, and at its left hand armature and back contact opens the circuit previously traced through the toll supervisory lamp 211 for giving the special operator a signal that the holding circuit has been seized through selector switches from the cordless position. Relay 210 upon energizing disconnects the windings of relay 208 from the strands of the holding cord circuit and establishes a direct metallic connection from the tip and ring conductors 317 and 319 at the final selector switch. Relay 210 at its right hand armature and front contacts connects the winding of slow to release ringing trip relay 216 through the back contact and left hand armature of relay 214 to the back contact and right hand armature of relay 201, but since relay 201 is at this time energized, this circuit is without effect.

As soon as sequence switch 300 of the final selector switch 350 left position 8½ following the units selection movement of the switch, the circuit previously traced over the bank terminal 449 and brush 451 of the cordless incoming selector switch, through the lower contact of sequence switch cam 415 (11) and thence over lead 456 to the cordless operator's sender is opened at sequence switch cam 305 of the final selector switch and the sequence switch associated with the sender is thereupon advanced into position 10. A circuit is now established for advancing sequence switch 400 of the incoming selector switch out of position 11 and into position 12. This circuit may be traced from grounded battery through the winding of the driving magnet of sequence switch 400, lower left hand contact of sequence switch cam 411 and thence to ground through sequence switch cam 427. As soon as sequence switch 400 leaves position 11, the circuit previously traced through lamp 429 and interrupter 430 is opened at the lower left hand contact of sequence switch cam 404 and the flickering signal which was produced by the lamp 429 during the setting of the selector switches is stopped to denote to the operator that selection is completed, and both lamps 423 and 429 are then connected into a circuit in which both lamps burn steadily. This circuit may be traced from grounded battery, through lamps 423 and 429, the right hand contacts of sequence

switch cam 404 and thence to ground through the contacts of sequence switch cam 407.

As soon as sequence switch 400 reaches position 12, if at this time the operator at the switching center Y has made connection by her cord circuit 108 with the assigned trunk, relay 421 will be energized over trunk line 416 and a circuit is established for relay 422 which may be traced from grounded battery through the left hand winding of this relay, lower left hand contact of sequence switch cam 402, upper right hand contact of sequence switch cam 403 and thence to ground at the armature and front contact of relay 421. Relay 422 upon energizing in this circuit closes a circuit for driving sequence switch 400 out of position 12 and into position 14. This circuit may be traced from grounded battery through the winding of the driving magnet of sequence switch 400, upper left hand contact of sequence switch cam 406, right hand armature and front contact of relay 422 and thence to ground at the left hand contact of sequence switch cam 407. With sequence switch 400 in position 14, the armatures of ringing relay 457 are connected over cams 414 and 415 to the tip and ring brushes 452 and 451 of the incoming selector switch and thence over the circuit established through the brushes of the final selector switch, the conductors 220 and 217 of the holding cord 200, tip and ring conductors of the truck circuit 103 and thence to the line of the calling subscriber. The toll operator at switching center Y may now converse with the calling subscriber and instruct him to restore his receiver to its switch-hook until he is recalled after the successful extension of the connection to the desired line.

The toll operator after being assured that a connection has been established, between her cord circuit and the calling subscriber's line proceeds to obtain the assignment of a toll line 109 extending to the exchange in which the desired line B terminates. After receiving an assignment of the toll line she then proceeds to connect the calling plug of her cord circuit 108 with the jack of the toll line. A connection from the toll line 109 is then established through the toll operator's position at the distant exchange and through the terminating operators' position of the office Z of such exchange to the line of the desired subscriber B.

The operator at the toll switching position now applies ringing current to the trunk 416 for recalling the calling subscriber, and ring down relay 458 is energized over a circuit extending from the tip conductor of the cordless trunk circuit 416, through the upper right hand winding of repeating coil 419, through condenser 479, winding of relay 458, lower right hand wind-

ing of repeating coil 419 and thence over relay 421 is again disconnected from the conductors of trunk circuit 416 causing the operation of a supervisory signal at the toll operator's position at the switching center Y to denote to the toll operator that the calling subscriber has responded to the application of ringing current and is ready to converse with the subscriber B in the distant exchange. 70

5 closes a circuit for relay 420 extending from grounded battery, right hand winding of relay 420, armature and front contact of relay 458 and thence to ground through the winding of ringing relay 457. Relays 420 and 10 457 both energize in this circuit, relay 420 disconnecting the windings of relay 421 from the conductors of the trunk circuit 416 and maintaining relay 421 energized over a circuit extending from grounded battery through the left hand winding of relay 421 and thence to ground through make contacts of the right hand armature of relay 420. Relay 457 upon energizing attracts its armatures for connecting a source of ringing current 459 and ground to the ring and tip brushes 451 and 452 respectively of the incoming selector switch. Ringing current is thus applied to the line of the calling subscriber over a circuit which may be traced 15 from the source of ringing current 459, lower armature and front contact of relay 457, the upper contact of sequence switch cam 415, brush 451, bank terminal 449, conductor 319, upper contacts of sequence switch cam 305 brush 353 and bank terminal 357 of the final selector switch 350, conductor 217 of the holding cord circuit 200, inner left hand armature and front contact of relay 210, conductor 218, ring contacts of plug P and jack J, ring conductor of trunk circuit 103, lowermost brushes of the selector switch 101 and line switch 100 through the bell and condenser of the calling subscriber's station A, upper brushes of line switch 100 and selector switch 101, tip conductor of trunk 103, tip contacts of jack J and plug P, conductor 219, outer left hand armature and front contact of relay 210, conductor 220, bank terminal 359 and brush 452 of the final selector switch 350, lower contacts of sequence switch cam 302, trunk conductor 317, bank terminal 450 and brush 452 of the incoming selector switch 418, upper contacts of sequence switch cam 414 and thence to ground at the make contacts of the upper armature of relay 457. 20

45

50

When the calling subscriber responds to the application of ringing current by removing his receiver from its switch hook during the period when ringing relay 457 is de-energized, a circuit is established as previously traced from the substation of the calling line, through the windings of supervisory relay 461 and this relay energizes, closing a circuit from grounded battery, through the left hand winding of relay 420, armature and front contact of relay 461 and thence to ground at the armature and front contact of relay 421. When relay 420 responds following the operation of relay 461, 55

With sequence switch 400 in position 14 75 and relay 422 held energized through the circuit previously traced to ground at the armature and front contact of relay 421, the circuit for lamp 429 is maintained until conversation is completed. This circuit may be 80 traced from grounded battery through lamp 429, the lower right hand and upper left hand contacts of sequence switch cam 404, left hand armature and front contact of relay 422 and thence to ground through the 85 left hand contacts of sequence switch cam 405. Lamp 423 is not at this time illuminated.

The subscribers A and B are now connected to a circuit over which conversation 90 may take place, which circuit may be traced in Fig. 1 through the brushes of line switch 100, brushes of selector switch 101 over the trunk circuit 103, holding cord circuit 200, brushes of final selector switch 350, brushes 95 of cordless selector switch 418, trunk 416, the toll cord circuit 108 at the toll switching center Y, toll line 109 and thence over the cord circuit in the office Z of the distant exchange, talking current being supplied 100 to the calling subscriber through the windings of relay 461 of the incoming selector switch at the cordless operator's position O' and talking current being supplied 105 to the called subscriber from the terminating operator's cord circuit in the office Z.

The operator at the switching center Y has full supervision of the connection from the time she receives the assignment of the cordless trunk circuit and neither the special 110 A operator nor the cordless operator need give further attention to the connection until it becomes necessary to take it down. Thus, the special A operator and the cordless operator are free during the setting up and continuance of the toll connection to employ the other apparatus at their respective positions in the most economical manner. Were it necessary for the special operator 115 to remain in on a connection until after the termination of conversation over the toll connection, it would practically result in the tying up of all of her apparatus for that period, as on toll connections it is necessary for the supervising operator to note the time 120 elapsing during the conversation for assessment purposes.

Upon the termination of the conversation 125 both subscribers restore their receivers to their switch hooks, the restoration of the re- 130

ceiver to the switch hook at the called substation B causing in the well known manner the operation of a supervisory signal at the toll operator's cord circuit 108 in the toll switching center Y. The restoration of the receiver at the calling substation A opens the circuit of relay 461 which upon deenergizing opens the circuit of relay 420, thus re-connecting the windings of relay 421 to the conductors of the trunk circuit 416, which thereupon in the well known manner causes the operation of a supervisory signal at the switching center Y, to inform the toll operator at that position that the conversation is completed and that she may take down the connection at her position.

As soon as she removes the answering plug or her cord circuit 108 from the jack of the cordless trunk circuit 416, the relay 421 becomes deenergized and opens the circuit of relay 422, which upon deenergizing opens the circuit previously traced through lamp 429 and closes circuits for flashing both lamps 423 and 429. The circuit of lamp 423 may be traced from grounded battery through lamp 423, right hand contact of sequence switch cam 407, right hand armature and back contact of relay 422 and thence through the right hand contact of sequence switch cam 408 and interrupter 462 to ground. The circuit of lamp 429 may be traced from grounded battery through lamp 429, lower right hand and upper left hand contacts of sequence switch cam 404, left hand armature and back contact of relay 422, upper left hand and lower right hand contacts of sequence switch cam 408 and thence to ground through interrupter 462. The operator at the cordless position in response to the flashing of lamps 423 and 429 operates the disconnect key 463. A circuit is now established which may be traced from grounded battery through the winding of the driving magnet of sequence switch 400, lower right hand contact of sequence switch cam 411, and thence to ground through the contact of key 463 for driving sequence switch 400 out of position 14 and into position 18. A circuit is now established for the down drive magnet 464 which may be traced from grounded battery through the winding of magnet 464 and thence to ground through the right hand contact of sequence switch cam 413. Magnet 464 upon energizing presses the depending portion of the switch shaft 434 against the constantly rotating down drive roller 465 thereby causing the downward movement of switch shaft 434 into its normal position.

When the switch shaft reaches its normal position a circuit is established for driving sequence switch 400 into its normal position which circuit may be traced from grounded battery through the winding of the driving magnet of the sequence switch, upper left

hand contact of sequence switch cam 411, normal segment 466 of the commutator 439, brush 455 and thence to ground at the upper contact of sequence switch cam 413. The circuits of the cordless incoming selector are now in normal position and the sending mechanism is dis-associated from the circuits of the incoming selector as soon as sequence switch 400 leaves position 18.

As soon as sequence switch 400 of the incoming selector switch reaches position 16 $\frac{1}{4}$, the circuit previously traced over brush 446, bank terminal 448 conductor 325, right hand armature and front contact of relay 321, armature and back contact of relay 324 to grounded battery through the right hand winding of relay 321 is opened and relay 321 deenergizes. Upon deenergizing this relay connects ground potential to the sleeve conductor 325 from ground through the right hand contact of sequence switch cam 314, right hand armature and back contact of relay 321, for the purpose of holding the circuit extending to the final selector 350 busy until the final selector switch is fully restored and sequence switch 300 of the final selector has returned to its normal position. At its right hand armature and back contact relay 321 closes a circuit extending from grounded battery through the right hand winding of relay 318, the upper contacts of sequence switch cam 309, and thence to ground through the armature and back contact of relay 321. Relay 318 upon energizing, establishes a circuit for driving sequence switch 300 out of position 15 and into position 16, this circuit extending from grounded battery, winding of driving magnet of sequence switch 300, lower left hand contact of sequence switch cam 312, right hand armature and front contact of relay 318, and thence to ground through the upper contact of sequence switch cam 308. When the sequence switch reaches position 15 $\frac{1}{2}$, relay 318 deenergizes and at its right hand armature and back contact closes a circuit for driving sequence switch 300 out of position 16 and into position 17. This circuit may be traced from grounded battery through the winding of the driving magnet of sequence switch 300, upper left hand contact of sequence switch cam 312, right hand armature and back contact of relay 318 and thence to ground through the upper contact of sequence switch cam 308. A circuit is now established for driving sequence switch 300 out of position 17 and into position 18 extending from grounded battery through the winding of driving magnet of sequence switch 300, lower left hand and upper right hand contacts of sequence switch cam 309 and thence to ground at the left hand armature and back contact of relay 321.

With sequence switch 300 in position 18,

a circuit is established for down drive magnet 344 which may be traced from grounded battery through the winding of magnet 344, lower contact of sequence switch cam 311, 5 upper left hand contact of sequence switch cam 307, upper right hand contact of sequence switch cam 306, and thence to ground. Magnet 344 upon energizing presses the depending portion of the switch shaft 327 against the constantly rotating down drive roller 345, thereby moving the switch shaft 327 down into its normal position. When the switch shaft reaches normal position a circuit is closed 10 for driving sequence switch 300 out of position 18 and into its normal position 1. This circuit may be traced from grounded battery through the winding of the driving magnet of sequence switch 300, upper right hand contact of sequence switch cam 312, 15 conductor 346, normal segment 347 of commutator 331, brush 338, conductor 333 and thence to ground through the upper right hand contact of sequence switch cam 306. 20 The circuits of the final selector switch are now in normal condition.

As soon as sequence switch 300 left position $16\frac{1}{4}$, battery potential was disconnected at sequence switch cam 313 from the 25 circuit previously traced through brush 342, bank terminal 343, sleeve conductor 215 and the winding of relay 209. Relay 209 thereupon deenergizes, opening the circuit of relay 210. Upon the deenergization of relay 35 209 the circuit of the toll supervisory lamp 211 is again established from grounded battery, through lamp 211, the left hand armature and back contact of relay 209 and the right hand armature and front contact of 0 relay 201. The deenergization of relay 210, again connects the windings of relay 208 to the strands 218 and 219 of the cord circuit 200, but since the calling subscriber has restored his receiver to its switch hook relay 5 208 is not energized. However, since relay 209 is at this time deenergized, a circuit is established for the supervisory lamp 207 which may be traced from grounded battery through lamp 207, left hand armature and 0 front contact of relay 201, armature and back contact of relay 208 and thence to ground at the right hand armature and back contact of relay 209. In response to the 5 illumination of lamps 207 and 211 the operator at position 0 removes the plug P from the jack J. The circuit previously traced through relays 201 and 204 is now opened, relay 201 deenergizing to open the circuits of lamps 207 and 211, and relay 204 deenergizing to open the circuit of relay 205 which in turn disconnects ground potential from sleeve conductor 206 of the trunk circuit 103 thereby initiating the restoration of the district selector switch 101 and line 0 switch 100 of the full mechanical office X.

All apparatus which has been employed in the connection is now restored to normal condition.

If through error a calling subscriber in the full mechanical office sets a final selector switch upon the terminals of a holding cord circuit 200 which is not in use at the special operator's position 0, the circuits of the holding cord will function in the following manner when the holding cord is seized by the final selector switch:—Upon the engagement of the test brush 342 of the final selector switch with the bank terminal 343 of the holding cord 200, with the sequence switch 300 of the final selector switch in position 15, a circuit as previously traced over conductor 215 and through the winding of relay 209 is established and relay 209 becomes energized in this circuit. Upon energizing, relay 209 closes the previously traced circuit for relay 210. Since the cord circuit is not in use, plug P is not in jack J and relay 201 is not therefore energized. However, upon the energization of relay 209 a circuit is established for the toll lamp 211 which may be traced from grounded battery, through the lamp, left hand armature and front contact of relay 209 and thence to ground at the right hand armature and back contact of relay 201. Relay 210 upon energizing closes a circuit for slow to release relay 216, which may be traced from grounded battery through the winding of relay 216, right hand armature and front contact of relay 210, left hand armature and back contact of relay 214 and thence to ground at the right hand armature and back contact of relay 201.

The operator noting the illumination of lamp 211 presses the listening key 212 to connect her telephone set to the seized holding cord 200 and thereby establishes a circuit for relay 214, which may be traced from grounded battery through the left hand winding of relay 214 and thence to ground at the contacts 213 of the key 212. The operation of relay 214, opens the circuit of relay 216 and at its left hand armature and front contact connects ground through resistance element 221, armature and front contact of relay 216, ring conductor 217 of the cord circuit 200, during a period measured by the time required for relay 216 to release for the purpose of tripping ringing current at the incoming selector switch over which the connection has been established. The operator, upon the termination of the application of ringing current, may then converse with the calling subscriber and inform the subscriber that he has made an erroneous connection.

If the cordless operator through error sets the final selector switch 350 upon the terminals of a holding cord 200, which has not been taken for use, the holding cord circuit 130

functions in the manner previously described except that the connection of ground to the ring conductor of the cord circuit does not cause the tripping of the ringing current at 5 the cordless operator's position, since ringing current is manually applied through the operation of a ringing key at the tool operator's position. When the operator at the special operator's position 0 becomes connected to the holding cord circuit 200, through contacts of key 212 a circuit is then established for the relay 461 at the cordless incoming selector switch which in the manner previously described operates the supervisory signal at the toll operator's position. The special operator may then converse with the toll operator and transmit to her the information that the connection has been inaccurately made and may also 10 transmit to the operator the correct number of the holding cord which she has employed. In the case of an erroneous connection the circuits at the cordless operator's position and the final selector switch 350 which has 15 been employed are restored to normal condition in the manner previously described.

When the cordless incoming selector 418 is hunting for an idle final selector switch which has access to the desired holding 20 cord 200, it may happen that all idle final selector switches are at the time busy. The incoming selector switch will then be driven to an overflow position immediately above the selected group of trunk circuits extending 25 to the desired group of final selector switches. With the switch in the overflow position and the sequence switch 400 in the trunk hunting position 9, relay 422 deenergizes closing at its right hand armature 30 and back contact a circuit for driving sequence switch 400 out of position 9 and into position 11. This circuit may be traced from grounded battery through the winding of the driving magnet of sequence 35 switch 400, lower left hand contact of sequence switch cam 406, right hand armature and back contact of relay 422 and thence to ground at the left hand contact of sequence switch cam 407. With sequence 40 switch 400 in position 11 and the selected set of brushes in the overflow position, shaft brush 437 is in contact with an overflow 45 segment of commutator segment 438 and a circuit is therefore established for advancing sequence switch 400 out of position 11 and into position 12. This circuit may be traced from grounded battery, through the winding of the driving magnet of sequence switch 400, upper right hand contact of sequence switch cam 411, conductor 467, commutator segment 438, brush 437, and thence 50 to ground at the upper contact of sequence switch cam 413. Since at this time relay 421 is energized over the cordless trunk cir-

cuit 416 a circuit is now effective for energizing relay 422, which circuit may be traced from grounded battery, left hand winding of relay 422, lower left hand contact of sequence switch cam 402, upper right hand contact of sequence switch cam 403 and 55 thence to ground at the armature and front contact of relay 421. Relay 422 upon energizing closes a circuit for driving sequence switch 400 out of position 12 and into position 14. This circuit extends from grounded battery, through the winding of the driving magnet of sequence switch 400, upper left hand contact of sequence switch cam 406, right hand armature and front contact of relay 422 and thence to ground at the 60 left hand contact of sequence switch cam 407. A circuit is now effective as previously traced over the upper right hand contact of sequence switch cam 411 and the overflow segment of commutator segment 438 for advancing sequence switch 400 out of position 14 and into position 17. A circuit is now effective for connecting the supervisory lamp 423 in series with interrupter 430 causing lamp 423 to flicker to apprise the operator of the fact that all trunks in the selected group are busy. This circuit may be traced from grounded battery through lamp 423, right hand contact of sequence 65 switch cam 407, right hand armature and front contact of relay 422, right hand contacts of sequence switch cam 412 and thence to ground through interrupter 430.

If the selector switch 418 fails to function properly and is driven upwardly to the top 70 of its bank of terminals a circuit is closed for advancing sequence switch 400 out of any position between positions 4 and 9 into position 10 for arresting the upward movement of the switch shaft thereby preventing injury to its mechanism. This circuit may be traced from grounded battery through the winding of the driving magnet of sequence switch 400, upper right hand contact of sequence switch cam 406, (2 to 75 9) conductor 468, telltale segment 469 of the commutator 439, brush 455, conductor 136 and thence to ground either through the upper contact of sequence switch cam 413 in positions 10 to 8, or to ground 80 through the upper contacts of sequence switch cam 412 in position 9 and thence through the right hand armature and front contact of relay 422 and the left hand contact of sequence switch cam 407. In the tell tale position of the switch the usual tell tale signals are lighted on the frame upon which the switch is located for the purpose of attracting the attention of the switchboard attendant.

What is claimed is:

1. In a telephone exchange system, an originating office, a second office, a trunk

line extending between said offices, a subscriber's line terminating in said first office, means for extending a connection from said subscriber's line to said trunk line, and 5 means at said first office for maintaining another connection with said subscriber's line after said first mentioned connection has been disestablished.

2. In a telephone exchange system, an 10 originating office, a second office, a trunk line extending between said offices, a subscriber's line terminating in said first office, means for extending a connection from said subscriber's line to said trunk line, and a holding 15 cord circuit at said first office for maintaining another connection with said subscriber's line, after said first mentioned connection has been disestablished.

3. In a telephone exchange system, an 20 originating office, a second office, a trunk line extending between said offices, a subscriber's line terminating in said first office, means for extending a connection from said subscriber's line to said trunk line including 25 selector switches and an operator's cord circuit, and a holding cord circuit at said operator's position for maintaining another connection through said selector switches with said subscriber's line after said first 30 mentioned connection has been disestablished by the disconnection of said first mentioned cord circuits.

4. In a telephone exchange system, an 35 originating office, a second office, a trunk line extending between said offices, a subscriber's line terminating in said first office, means for extending a connection from said subscriber's line to said trunk line including selector switches and operator's cord circuit, 40 and a holding cord circuit at said operator's position for maintaining another connection through said selector switches with said subscriber's line after said first mentioned connection has been disestablished by the disconnection of said first mentioned cord circuit and after said subscriber has returned 45 his receiver to its switch hook.

5. In a telephone exchange system an 50 originating office, an intermediate office, a terminating office, a trunk line extending between said first named offices, a calling subscriber's line terminating in said first office, a subscriber's line terminating in said terminating office, means for extending a 55 connection from said calling subscriber's line to said trunk line, means at said intermediate office for extending a connection to said terminating office, means at said first office for maintaining another connection with said subscriber's line after said first 60 mentioned connection has been disestablished, and means for extending a connection from said intermediate office to said holding means whereby said subscribers' lines are

interconnected through said holding means, 65 said last named means and said connection extending means of said intermediate office.

6. In a telephone exchange system, an originating office, an intermediate office, a terminating office, a trunk line extending between said first named offices, a calling subscriber's line terminating in said first office, a called subscriber's line terminating in said terminating office, an operator's position in each of said offices, means for extending a connection from said calling line to the operator's position in said first office, means for establishing a call circuit over said trunk line between the operators' positions in said first named offices, means for extending a connection between the operator's position of said intermediate office and said called line, a holding cord at the operator's position of said first office for maintaining another connection with said calling line after said first mentioned connection with said calling line has been disestablished, and means for extending a connection from the operator's position of said intermediate office to said holding cord. 70 75 80 90

7. In a telephone exchange system, an originating office, an intermediate office, a terminating office, a trunk line extending between said first named offices, a calling subscriber's line terminating in said first office, a called subscriber's line terminating in said terminating office, an operator's position in each of said offices, means for extending a connection from said calling line to the operator's position in said first office, means for establishing a call circuit over said trunk line between the operators' positions in said first named offices, means for extending a connection between the operator's position of said intermediate office and said called line, a holding cord at the operator's position of said first office for maintaining another connection with said calling line after said first mentioned connection with said calling line has been disestablished, and means for extending a connection from the operator's position of said intermediate office to said holding cord. 95 100 105 110

8. In a telephone exchange system, an originating office, an intermediate office, a terminating office, a trunk line extending between said first named offices, a calling subscriber's line terminating in said first office, a called subscriber's line terminating in said terminating office, an operator's position in each of said offices, means for extending a connection from said calling line to the operator's position in said first office, means for establishing a call circuit over said trunk line between the operators' positions in said first named offices, means for extending a connection between the operator's position of said intermediate office and said called 115 120 125

line, a holding cord at the operator's position of said first office for maintaining another connection with said calling line after said first mentioned connection with 5 said calling line has been disestablished, supervisory means associated with said holding cord, means for extending a connection from the operator's position of said intermediate office to said holding cord, and 10 means operative upon the establishment of said latter connection to transfer supervision from said holding cord to the operator's position at said intermediate office.

9. In a telephone exchange system, an originating office, an intermediate office, a terminating office, a trunk line extending between said first named offices, a calling subscriber's line terminating in said first office, a called subscriber's line terminating in 15 said terminating office, an operator's position in each of said offices, means for extending a connection from said calling line to the operator's position in said first office, means for establishing a call circuit over 20 said trunk line between the operators' positions in said first named offices, means for extending a connection between the operator's position of said intermediate office and said called line, a holding cord at the operator's position of said first office for maintaining 25 another connection with said calling line after said first mentioned connection with said calling line has been disestablished, a signal associated with said holding cord, 30 means for extending a connection from the operator's position of said intermediate office to said holding cord, and means operative upon the establishment of said latter connection to operate said signal if said holding cord is not at the time in use.

10. In a telephone exchange system, an originating office, an intermediate office, a terminating office, a trunk line extending between said first named offices, a calling 45 subscriber's line terminating in said first office, a called subscriber's line terminating in said terminating office, an operator's position in each of said offices, means for extending a connection from said calling line to the operator's position in said first office, means for establishing a call circuit over 50 said trunk line between the operators' positions in said first named offices, means for extending a connection between the operator's position of said intermediate office and said called line, a holding cord at the operator's position of said first office for maintaining 55 another connection with said calling line after said first mentioned connection with said calling line has been disestablished, a signal associated with said holding cord, means for extending a connection from the operator's position of said intermediate office to said holding cord and for applying ring- 60 ing current to said calling line, means op-

erative upon the establishment of said latter connection to operate said signal if said holding cord is not at the time in use, and means operative upon the response of the operator to cut off said ringing current. 70

11. In a telephone exchange system, an originating office, a second office, an operator's position in said first office, a subscriber's line terminating in said first office, means for extending a connection from said subscriber's line to said operator's position, means under the control of the operator for establishing a connection between her position and said second office, and means at 80 said first office for maintaining another connection with said subscriber's line after said first mentioned connection has been disestablished.

12. In a telephone exchange system, an originating office, a second office, an operator's position in said first office, a subscriber's line terminating in said first office, means for extending a connection from said subscriber's line to said operator's position, means under the control of the operator for establishing a connection between her position and said second office, and a holding cord circuit at said first office for maintaining another connection with said subscriber's line after said first mentioned connection 90 has been disestablished.

13. In a telephone exchange system, the method of establishing toll connections between subscribers' lines in widely separated offices which consists in extending a connection from a calling subscriber's line in an originating office to a special operator's position, establishing a connection with such extended line and obtaining the designation of the line desired, establishing a holding connection with such extended line, transmitting the designation of the line desired and the designation of the holding connection to a toll switching center, disestablishing the initial connection with the extended calling line whereby the special operator is freed for the performance of other duties, building back a connection from the switching center to the extended calling line over the holding connection and extending such built back connection through the switching center to the desired line. 100 105 110 115

14. In a telephone exchange system, the method of establishing toll connections between subscribers' lines in widely separated offices which consists in extending a connection from a calling subscriber's line in an originating office to a special operator's position, establishing a connection with such extended line and obtaining the designation of the line desired, establishing a holding connection with such extended line, transmitting the designation of the line desired and the designation of the holding connection to a toll switching center, disestablish- 120 125 130

ing the initial connection with the extended calling line, transmitting the designation of the holding connection to a cordless operator in the originating office, building back a connection from the switching center to the extended calling line over the holding connection under control of the cordless

operator, and extending such built back connection through the switching center to the desired line.

10

In witness whereof, I hereunto subscribe my name this 14th day of October A. D., 1920.

JOHN W. GOODERHAM.
